CLAIM

The ornamental design for an elevated pet feeder, as shown and described.

DESCRIPTION

FIG. 1 is a front perspective view of an elevated pet feeder in accordance with my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines and unshaded portions contained within broken lines depict exemplary elements of the feeder that are shown for illustrative purposes only and that form no part of the claimed design.

1 Claim, 4 Drawing Sheets(56)
